CLAIM

The ornamental design for a trash can tableware retriever, as shown and described.

DESCRIPTION

FIG. 1 is a perspective view of a trash can tableware retriever embodying my new design.

FIG. 2 is a front view of the trash can tableware retriever of FIG. 1 and the rear view is a mirror image thereof.

FIG. 3 is a left side view of the trash can tableware retriever with the right side view being a mirror image thereof.

FIG. 4 is a top view thereof; and,

FIG. 5 is a bottom view.
